UNITED STATES PATENT OFFICE

169,980

CRAYON SHARPENER

Mary C. Knapp, Bradenton, Fla.

Application May 22, 1952, Serial No. 19,830

Term of patent 14 years

(Cl. D74—21)

To all whom it may concern:

Be it known that I, Mary C. Knapp, a citizen of the United States of America, residing at Bradenton, in the county of Manatee and State of Florida, has invented a new, original, and ornamental Design for a Crayon Sharpener, of which the following is a specification, reference being had to the accompanying drawing, forming a part thereof, wherein:

Figure 1 is a view in side elevation of a crayon sharpener, showing my new design.

Figure 2 is a view in front elevation of the same.

Figure 3 is a top plan view of the same.

Figure 4 is a view in rear elevation of the same.

Figure 5 is a bottom plan view of the same.

I claim:

The ornamental design for a crayon sharpener, as shown.

MARY C. KNAPP.
